DESIGN FOR A PORTABLE POWER DRIVEN HAND TOOL UNIT

Gilbert B. Larson, Geneva, Ill., assignor to Independent Pneumatic Tool Co., Chicago, Ill., a corporation of Delaware

Application October 26, 1939, Serial No. 87,868

Term of patent 14 years

To all whom it may concern:

Be it known that I, Gilbert B. Larson, a citizen of the United States, residing at Geneva, in the county of Kane and State of Illinois, have invented a new, original, and ornamental Design for a Portable Power Driven Hand Tool Unit, of which the following is a specification, reference being had to the accompanying drawing, forming a part thereof, and in which

Fig. 1 is a side elevational view of a portable power driven hand tool unit showing my new design;

Fig. 2 is a front elevational view thereof with the chuck member omitted for convenience of illustration;

Fig. 3 is a rear view; and

Fig. 4 is an elevational view of the opposite side of said tool from that shown in Fig. 1:

The dominant features of my design reside in the portions shown in full lines.

I claim:

The ornamental design for a portable power driven hand tool unit, as shown and described.

GILBERT B. LARSON.
